F. J. MATCHETTE.
 AUTOMATIC VACUUM GOVERNOR.
 APPLICATION FILED DEO. 18, 1908. RENEWED JAN. 22, 1913.
1,071,936. Patented Sept. 2, 1913.

UNITED STATES PATENT OFFICE.

FRANK J. MATCHETTE, OF MILWAUKEE, WISCONSIN.

AUTOMATIC VACUUM-GOVERNOR.

1,071,936.

Specification of Letters Patent. Patented Sept. 2, 1913.

Application filed December 18, 1908, Serial No. 468,109. Renewed January 22, 1913. Serial No. 743,655.

To all whom it may concern:

Be it known that I, FRANK J. MATCHETTE, a citizen of the United States, residing at Milwaukee, in the county of Milwaukee and State of Wisconsin, have invented 5 certain new and useful Improvements in Automatic Vacuum-Governors, of which the following is a specification, reference being had to the accompanying drawing, 10 forming a part thereof.

This invention relates to means for automatically controlling the supply of a fluid pressure medium such as steam, to vacuum producing means such as a pump or aspirator, according to variations in the vacuum within certain limits. Its main object is to 15 simplify and improve the construction and operation of devices of this class.

It consists in the novel construction, arrangement and combination of parts as hereinafter particularly described and as 20 defined in the appended claims.

In the accompanying drawing like characters designate the same parts in both 25 figures.

Figure 1 is an elevation and partial section on the line 1—1, Fig. 2 of apparatus embodying the invention; and Fig. 2 is a 30 vertical longitudinal section on the line 2—2, Fig. 1, of the main valve forming a part of the apparatus.

The main valve case *a* having inlet and outlet connections *b* and *c* for the fluid pressure medium which is controlled by the 35 governor and which operates vacuum producing means such as a pump or aspirator, has between said connections a port and a valve seat *d*. In line with the port and valve seat the case is formed on the upper 40 side with an opening in which a removable cap *e* formed with a stuffing box is threaded. A valve *f* formed or provided with a stem *g* passing through and guided in the stuffing box, is fitted to said seat and 45 arranged to close against the pressure of the medium it controls toward the inlet *b*.

On one side the valve case is provided with a horizontal bracket or arm *h* having a vertical cylindrical opening adjacent to 50 its outer end. In this opening is fitted and secured by a nut *i* the tubular threaded stem *j* of a cylinder or vacuum chamber *k*. This cylinder or chamber is open at its upper end and provided with a removable 55 head or cover *l* having a central flanged opening and an air inlet and outlet *m*.

This inlet and outlet consists of one or more openings *o* in the head or cover, surrounded by a rim or flange projecting upwardly from the cover and protected by a 60 screen *p* and a removable cap *q* which prevent the admission of dust and dirt with air into the cylinder or chamber. A piston *r* provided with suitable packing, is fitted in the cylinder or chamber *k*, and has 65 a stem or rod *s* extending upwardly through and guided in the flanged opening of the head or cover *l*, and preferably also downwardly into the tubular stem *j*. A lever *t* pivoted at one end to the upper end of 70 the piston rod *s* and pivotally connected at the other end by a link *u* with the valve case *a*, engages with the upper end of the valve stem *g*.

To insure the opening of the main valve *f* 75 in case the pressure of the medium it controls is insufficient, or the piston *r* sticks or binds in the cylinder or chamber *k*, a spring *v* which tends to force the piston upward, is inserted in the tubular neck *j* 80 around the lower end of the piston rod *s*.

The cylinder or vacuum chamber *k* is connected below the piston *r* through the tubular stem *j* by a pipe *w* with auxiliary valve mechanism whereby communication 85 is established between the lower end of said cylinder or chamber and a source of vacuum or the atmosphere, according to variations within predetermined limits of the vacuum produced by the medium under the control 90 of the main valve *f*. For this purpose suitable automatic mechanism such as that shown in connection with the main valve and its motor in Fig. 1 may be employed. This mechanism comprises a casing *2*, 95 closed at the ends by caps *3* and piston valves *4* and *5*, which are pressed toward each other and the center of the casing *2* and normally held against a stop *6* by springs *7*, the valves being hollow or recessed and open at their outer ends to receive the springs. The outer ends of the springs are seated against flanged followers *8* resting upon the points of adjusting screws *9* which are threaded in the caps *3*. 105

The casing is formed with a passage 10 communicating with the outer recessed ends of the piston valves and connected by a pipe 11 with a source of vacuum (not shown) which is controlled by the main valve *f*. It 110 is also formed with a passage *12* which communicates with the valve chamber through

ports 13 and 14 and is connected by the pipe *w* with the cylinder or vacuum chamber *k* of the main valve motor, and it has one or more ports 15 opening from the valve chamber between the valves to the atmosphere.

5 The valve 4 is formed with an annular port 16, connected by radial passages with the spring chamber or recess and adapted to register when the valve is moved outward, with the port 13. The valve 5 is formed with 10 an annular port 17 which registers, when the valve is in its inner position against the stop 6, with the port 14 and constantly communicates with the port or ports 15 through one 15 or more longitudinal passages in the valve.

The apparatus hereinbefore described and constituting the governor, operates as follows: The several moving parts of the apparatus are shown in the positions they occupy 20 when the fluid pressure medium is shut off from the vacuum producing means and there is no vacuum acting upon the auxiliary valve mechanism. Under these conditions, when the fluid pressure medium is admitted to the main valve *f* it will lift said valve from its seat and pass through the case *a* in the direction indicated by arrows on Fig. 2, to the 25 vacuum producing means, which will thereupon exhaust air through the pipe 11 and passage 10 from the casing 2 at the outer ends of the valves 4 and 5. When the pressure 30 on the outer end of the valve 5 is reduced sufficiently to enable the atmospheric pressure on the inner end of the valve to overcome the tension of the spring 7, said 35 valve will be moved to the right and close the port 14, thereby cutting off communication between the lower end of the cylinder *k* and the atmosphere, and when the pressure 40 on the outer end of the valve 4 is reduced sufficiently to enable the atmospheric pressure on the inner end of the valve to overcome the tension of the associated spring 7, said 45 valve will be moved to the left and carry the port 16 into register with the port 13, thereby establishing communication 50 through the pipe *w*, passage 12, ports 13 and 16, passage 10 and pipe 11 with the source of vacuum. The air will thereupon be exhausted 55 from the cylinder *k* below the piston *r* and said piston will be drawn down against the tension of the spring *v* and close the main valve *f* against the pressure of the medium which operates the vacuum producing 60 means. The valve *f* will remain closed and the vacuum producing means inoperative until the vacuum or pressure in the casing 2 on the outer end of the valve 4 is reduced 65 sufficiently to release said valve and permit it to be moved back to the right by the spring 7 acting thereon. When this occurs the port 13 is closed and communication between the source of vacuum and the motor cylinder *k* is cut off. A further reduction of the vacuum or pressure in the

casing 2 at the outer ends of the valves 4 and 5, releases the valve 5, permitting it to be moved back to the left by the spring 7 acting thereon. This brings the port 17 into register with the port 14 and establishes 70 communication between the lower end of the motor cylinder *k* and the atmosphere, through the pipe *w*, passage 12, ports 14 and 17 and ports 15. Thereupon aid will be admitted to the cylinder *k* below the piston *r* 75 and the atmospheric pressure on the upper side of the piston will be balanced. The pressure of the fluid medium controlled by the valve *f*, aided by the spring *v* will lift said valve from its seat, and move the piston 80 *r* upward in the cylinder *k*. The pressure medium being thus admitted to the vacuum producing means, the vacuum will be restored thereby to the limit for which the auxiliary valve mechanism or the spring 7 85 acting upon the valve 4 is adjusted. These operations will be automatically repeated as above explained, and the vacuum producing means will be started and stopped at predetermined limits of the vacuum produced 90 thereby, according to the adjustment of the springs 7 of the auxiliary valve mechanism.

By the adjustment of the screws 9, the tension of the springs 7 may be varied so that the valve *f* will be opened and closed at 95 different minimum and maximum pressure limits. Increasing the tension of the spring 7 acting on the valve 5, raises the minimum limit of vacuum at which said valve will be opened by the spring and release and permit 100 the opening of the main valve *f*. Increasing the tension of the spring 7 acting on the valve 4, raises the maximum limit of vacuum at which said valve will be opened against the pressure of said spring and cause the 105 main valve *f* to close. In all adjustments of the auxiliary valve mechanism however, the valve 5 should be set to close before the opening of the valve 4, and hence the valve 4 to close before the opening of the valve 5. 110

The auxiliary valve mechanism may be connected directly with the vacuum producing means or with a reservoir, or any part of a system from which air is exhausted by such means. When the pressure of the 115 medium controlled by the main valve *f* is sufficient, the spring *v* acting on the motor piston *r* may be omitted.

Various changes in the details of construction and arrangement of parts of the apparatus may be made without departing from the principle and scope of the invention. 120

I claim:

1. In an automatic vacuum governor the combination of a valve adapted to control 125 the flow of a pressure medium and to be opened by the direct pressure of such medium, a vacuum chamber having a movable part, a lever connected with said movable part and adapted to close said valve against 130

the pressure of said medium when a certain degree of vacuum is produced in said chamber, and means adapted to automatically establish and close communication between 5 said chamber and a source of vacuum according to variations in the degree of vacuum.

2. In an automatic vacuum governor the combination of a valve adapted to control 10 the flow of a pressure medium and to be opened by the pressure of said medium thereon, a vacuum chamber having a movable part, a lever connected with said movable part and adapted to close said valve 15 when a certain degree of vacuum is produced in said chamber, a spring acting on said movable part in opposition to the vacuum and tending to release the valve, and automatic means adapted to establish and 20 close communication between said chamber and a source of vacuum according to variations in the degree of the vacuum.

3. In an automatic vacuum governor the combination of a valve adapted to control 25 the flow of a pressure medium, a vacuum chamber having a movable part connected with said valve and adapted to close the same when a certain degree of vacuum is produced in said chamber, and automatic 30 means adapted to alternately close communication between said chamber and the atmosphere and open communication between said chamber and a source of vacuum and to close communication between said chamber 35 and the source of vacuum and open communication between said chamber and the atmosphere according to variations in the degree of the vacuum.

4. In an automatic vacuum governor the 40 combination of a valve case having a bracket on one side and a stuffing box, a valve seated in said case to open with the pressure of the medium which it controls and having a stem projecting through said stuffing box, a vacuum 45 chamber mounted on said bracket and having a movable part, a lever connected with said movable part and by a link with said case and adapted to engage with the valve stem and to close the valve against the 50 pressure of the medium which it controls

when a certain degree of vacuum is produced in said chamber, and automatic means adapted to open and close communication between said chamber and a source of vacuum.

55

5. In an automatic vacuum governor the combination of a valve case provided with a bracket projecting therefrom and formed with an opening, a valve seated in said case to close against the pressure which it controls and having a stem projecting through one side of the case, a vacuum chamber formed with a tubular stem which is fitted and secured in the opening in said bracket, a piston fitted in said chamber, a lever pivotally connected with the valve case and with said piston and engaging with the stem of the valve, and auxiliary valve mechanism connected with said tubular stem and adapted to automatically establish communication 60 between said chamber and a source of vacuum or the atmosphere according to variations in the degree of vacuum.

6. In an automatic vacuum governor the combination of a valve case having a bracket 75 extending therefrom and formed with a cylindrical opening, a valve seated in said case against the pressure of the medium which it controls, a vacuum chamber having a protected opening to the atmosphere and 80 a cylindrical stem which is fitted and secured in the opening of said bracket, a piston fitted in said chamber between said stem and the opening to the atmosphere and having a rod passing through the wall of 85 the chamber opposite said tubular stem, a lever pivotally connected with the valve case and piston rod and engaging with the valve stem, and auxiliary valve mechanism connected with said tubular stem and adapted 90 to automatically establish communication between said chamber and a source of vacuum or the atmosphere according to variations in the degree of vacuum.

In witness whereof I hereto affix my signature in presence of two witnesses.
